UNITED STATES PATENT OFFICE.

WILLIAM W. JACKSON, OF PHILADELPHIA, PENNSYLVANIA, ASSIGNOR TO
THE MACKELLAR, SMITHS & JORDAN COMPANY, OF SAME PLACE.

DESIGN FOR A FONT OF PRINTING-TYPE.

SPECIFICATION forming part of Design No. 19,355, dated October 15, 1889.

Application filed September 16, 1889. Serial No. 324,107. Term of patent 14 years.

To all whom it may concern:

Be it known that I, WILLIAM W. JACKSON, a citizen of the United States, and a resident of Philadelphia, Pennsylvania, have invented 5 a Design for Type, of which the following is a specification.

My design for a font of ornamental type is fully illustrated in the accompanying typographical impression.

10 The leading features throughout the design are the arched upper transverse line of a number of the letters and the solid appearance given to the whole font.

The upper lines of the letters B, C, D, G, O, 15 P, Q, R, S, and T are arched, and the upper lines of the letters A, B, D, J, P, R, U, V, W, Y, and Z extend past the vertical lines. Each vertical and horizontal line of each letter is

flared at its end, and the vertical lines of the letters B, D, P, and R are disconnected from 20 the upper transverse line.

The lower-case letters, as well as the numerals, are in keeping with the general design of the upper-case letters.

I claim—

25 The design for a font of ornamental type, as described, and as shown in the annexed typographical impression.

In testimony whereof I have signed my name to this specification in the presence of two sub- 30 scribing witnesses.

WM. W. JACKSON.

Witnesses:

GEO. WM. WITHAM,
HERMAN METIUS.
